GRAVITY BALL COMPUTING APPARATUS

Chester Graff, Los Altos, Calif.

Application April 27, 1948, Serial No. 23,533

9 Claims. (Cl. 235—123)

1

This invention relates to computing apparatus, and more particularly to an apparatus for adding and subtracting, tallying or counting, by controlled gravity movement of balls or other free-moving objects.

The general purpose is to provide a compact and simple device, of keyless and gearless construction, enabling the user, by one finger pressure, to add and subtract numbers and amounts of varying numerical value.

Another object is to provide for instruction purposes, a device that gives physical demonstration of the process and effect of carrying and borrowing tens from one digit column to another as applied in written or mental addition and subtraction.

A further object is to provide a device for tallying or counting purposes by gravity movement of objects, and particularly where varying numbers of units are to be tallied or counted.

A still further object is to provide a computing device with a minimum of movable mechanical parts, rugged in construction, efficient in operation, and economical to manufacture, and to generally improve upon devices of the character described.

With the foregoing and other objects in view, which will be further explained herein, or apparent from this specification, one form in which the invention may be embodied is described herein and illustrated in the accompanying drawing, it being understood that changes in minor details may be resorted to without departing from the spirit of the invention which is defined in the appended claims.

In the drawing:

Fig. 1 is a front elevation of the invention.

Fig. 2 is an enlarged horizontal lateral transverse section on line 2—2 of Fig. 1.

Fig. 3 is an enlarged broken vertical lateral transverse section on line 3—3 of Fig. 1.

Fig. 4 is an enlarged broken perspective view of structure of a channel member.

Referring to the drawings in which like reference characters indicate corresponding parts in the several views, 10 indicates generally an elongated box-like channel case, having one or more elongated grooves 11 therein which are closed at their respective opposite ends by end plates 12.

When a plurality of grooves are employed they are relatively parallel. It is preferred that the casing have from four to six of the grooves 11 since that number very conveniently accommodates as many computing units as are necessary for computations by the average person, though,

since each groove operates mechanically independently, the number of grooves may be increased or decreased to any desired number, four being illustrated in the present example.

5 The grooves 11 receive therein elongated relatively parallel channel members 13 open at the top as at 13a and of a length to extend substantially the length of the grooves between the opposite end plates 12, the opening 13a being an elongated slot.

10 It will be observed that the grooves 11 are formed between elongated upstanding relatively spaced separator walls 14, the terminal front face portion of which are provided with elongated flanges 15 which overlie a side edge portion of the groove. It is apparent that the outer wall of the casing requires only one such flange, whereas the inner separator members have flanges which extend in opposite directions. The 15 flanges 15 serve to hold the channel members 13 within the grooves by engagement under the flanges of an inwardly inclined flanged lip portion 16 along each side of the open top 13a of each channel member. The channel members 20 may be slid into the grooves from an end prior to attachment of end plates 12. If desired, cross bars 20a may be secured transversely across the opposite ends of the channels and grooves to hold the ends of the channels in the grooves, in which 25 event the flanges 15 may be eliminated from the mechanical standpoint, but it is preferred to retain them for appearance and to provide better space for numerals hereafter mentioned.

Each channel member has at its bottom a plurality of longitudinally spaced resilient spring members 17 which foot on the inner bottom wall of the groove members and normally resiliently hold the bottom of the channels spaced as at 17a from the bottom of the grooves, and hold

30 the inclined lips 16 of the channels against the flanges 15. Approximately centrally of its length each channel member 13 is provided with a press button 19 or bridge across the slot opening 13a. These press buttons or bridges 19 are to provide a "total release" and are upraised as at 20b from the transverse plane of the openings 13a, for purposes to be described.

Readily slideable tally objects are mounted within the channel members and in the present 35 example balls 18 are employed for the purpose, the use of the term ball being generic to include any suitable slideable objects adaptable for the same purpose. The balls are of a diameter to readily roll in the channel and to rest on the bottom wall of the channel and extend somewhat be-

yond the slot opening 13a, as best shown in Figs. 2 and 3, the bridge or the button total release 19 having its wall upraised sufficiently so that the balls may pass thereunder.

Next adjacent to the total release press buttons 19, fixedly extending transversely across the front face of the casing and of all of the grooves and channels, is a ball-stop bar 20, which engages the balls 18 and prevents their passage thereby when the channels 13 are at normal raised position responsive to springs 17, the resilience of the springs and space 17a being such that the channels may be manually depressed sufficiently so that the balls may roll unimpeded under the stop bar, but at this point it may be stated that the stop bar 20 divides the channels into a register section 22, and a totalizer section 23, the channels of each section being of a length to hold eighteen balls exclusive of the space occupied by the press button total release 19 in the totalizer section.

Longitudinally of both the side walls 10a of the casing, and also of the separator members 14, the upper faces 14a are inscribed with columns of consecutive numbers 24 paralleling each of the channel columns 13 which contain balls 18, the numbers in the columns being longitudinally spaced a distance substantially equal to the diameter of the balls 18. For convenience these columns of consecutive numerals are indicated A, B, C, D, and E.

In the present illustration the arrangement is for computation in units of dollars and cents, in which case the central column C may omit the inscribed consecutive numerals, whereby a decimal point may be thus indicated between the columns for dollars and the columns for cents.

In the register section 22 at one side of the stop bar 20, the numbers in the columns are consecutive from 1 to 9 commencing with 1 at the stop bar. In the totalizer section 23 on the other side of the stop bar, there is first a skipped space in each numerical column for the total release press button 19. Then, in the two columns A and B for cents and in the first column D for dollars, the numerals commence adjacent the total release button and stop bar with numeral 2 and are consecutive up to 10 and are then continued consecutively on a down scale from 9 to 1, whereas in the last dollar column E (to the left in Fig. 1) the numerals are consecutively continuous, commencing next below the total release press button 19, and are consecutive on a downward scale continuously from 18 to 1 to the bottom of the column.

The balls 18 are illustrated herein as being disposed in the register section, since that would be their disposal at commencement of an operation, the separate channel columns being indicated F, G, H, and I for convenience of reference.

The first nine of the balls 18 next adjacent to the stop bar in the channel columns in the channels of the register section, collectively indicated in the respective columns F¹, G¹, H¹, and I¹, are preferably of a different color in each of the channels. The remainder of the balls in each column F², G², H², and I² may be a uniform color different from the colors used for the first nine balls, say red for the following illustration of operation. This variation of the coloring of the balls is for convenience of operation to afford an easily recognized differentiation between the several columns and as a facility to tell at a glance when a column has more than the nine digits, which would indicate that a numeral is to be carried

to the next decimal column. The mechanical parts, and the operation thereof, is in no way affected by the color of the balls.

In mechanical operation it will be noted that balls 18 are held in the register section by cross-bar 20 responsive to the upward pressure of springs 17 on the channel and that upon resiliently depressing the channels, either by pressure upon the balls therein or upon the total release 10 or press button 19, the balls may roll past the stop bar 20 from one section to the other, passing freely under the raised press button total release 19.

For purposes of addition, all of the balls are first cleared from the channels of the totalizer section 23 into the channels of the register section 22. The device is now held with the total section 23 lower than the register section 22. Numbers or amounts are entered in the totalizer section by pressing the ball immediately above the desired number showing on the channel case; for example, if it is desired to add the numeral 5, the ball 6 would be pressed, depressing the channel member so that five balls roll under stop bar 20 into the total section channel. When the pressure would be released on the ball 6, on which pressure has been exerted, all of the balls above it in the channel column move by gravity until the stop bar 20 is reached. Another ball in any column may now be passed to the total section in the same manner.

When more than 9 indicator balls are accumulated in a total channel column, as indicated by the red balls appearing in the total section, ten balls are returned to the register section 22 by tripping the device to bring the register section to a position lower than the total section, and by exerting pressure on the ball representing the digit to be retained in the column. One ball is then released from the register section to the total section in the column immediately to the left of the column from the total section from which the indicator balls have been removed from the total section to the register section.

As illustrative of this operation, if 5 and 4 have been added in the cents digit column F, and then 7 cents more is added in that column, there would be 16 balls in the column F of the total section, the lower 9 being one color and the upper 7 being red indicating it was time to carry 10 to the next decimal column G to the left. Since digits to be retained would be 6, the depressing of the channel would be by pressing on ball 6 and rolling the ten free balls back into the register section, then depressing ball 2 in the register section of the next decimal column G, thereby dropping one ball to the totalizer section in that decimal column. The balls would then register "1" in column G and "6" in column F, indicating a visual total of 16.

For purposes of subtraction, the larger number is first released as in the adding procedure. The device is now tipped to bring the register section to a position lower than the total section 65 and the number to be subtracted is released from the total section to the register section.

When the device is returned to adding position, the remainder is indicated by the number of balls remaining in the total section of the device.

As stated, the balls roll freely under the upraised total release press button 19, but since the pressure on this button likewise depresses the channel 13, all balls in one or more or all the columns may be returned from the total section

to the register section by pressure on this button, or all balls may be passed from all the columns of one section into the columns of the other section by pressing all the buttons 19 consecutively or simultaneously.

It will be observed that the numerals paralleling the balls in the column I are consecutive from 1 to 18. Since, in the present illustration, there are no further columns to the left to which a higher decimal numeral may be carried the total must be indicated in that column. But, as stated, additional columns may be employed, if desired.

It is to be understood that the numerals indicated in the numeral columns A, B, C, D, and E may be changed to suit the convenience and preference of the operator, some of whom may prefer to have all the columns in the total section run consecutively 1 to 18 from bottom to top, while others may prefer to have numerals 1 to 9 and the remainder blank in the columns A, B, C, and D, and retain the completely numbered column E to indicate a total above ten, because there is no further columns to carry over the accrued decimal. The numerals shown merely represent the preference of the inventor, and in no way affect the mechanical elements of the apparatus or the operation thereof.

Having thus described the invention, I claim:

1. A computing apparatus including a casing, an elongated channel member in said casing and having the top thereof open providing an elongated slot, said channel being adapted for slidably receiving therein a plurality of indicator tally objects, resilient means for supporting the channel normally in spaced relation to the inner bottom of the casing, and a stop means mounted on the casing transversely across the slotted opening of the channel intermediate the opposite ends thereof for releasably engaging tally objects in said channel.

2. A device of the character described including a casing having a plurality of elongated grooves therein, an elongated channel member in each of said grooves and of lesser depth than the grooves, said channels having the tops thereof open providing elongated slots, a plurality of tally objects slidable in said channels and extending through the slots thereof for engaging a stop means, spring means for resiliently supporting the channels normally in spaced relation to the bottom of the grooves, and a stop means mounted transversely of the casing and across the slotted openings of the channels intermediate the opposite ends thereof for releasably engaging tally objects in said channels.

3. In a computing apparatus, the combination of a plurality of relatively parallel elongated channel members resiliently supported in a casing, said channels having the tops thereof open providing an elongated slot, resilient means for normally supporting the channels in spaced relation to the inner bottom of the casing, a plurality of tally objects slidable in said channels and extending through the slot thereof for engaging a stop means, faces paralleling said channels for inscribing numerals thereon, a stop means transversely fixed across the slotted openings of the channels intermediate the opposite ends thereof for normally engaging the tally objects and for releasing the tally objects when the channel member is depressed, means intermediate the opposite ends of the channels for depressing the channel members to permit passage of tally objects past the stop means, the said tally objects being of a size to engage the stop means when

the channels are resiliently supported at normal raised position and to pass by the stop means when the channel member is depressed.

4. A device of the character described, including a casing, a plurality of resiliently supported elongated channel members in the casing, and having the tops thereof open providing elongated slots, said channels being adapted for slidably receiving therein a plurality of indicator tally objects, springs to resiliently support the channel members in normal spaced relation to the inner bottom of the casing, faces paralleling said channels for inscribing numerals thereon, and stop means transversely fixed across the slotted openings of the channels intermediate the opposite ends thereof for releasably impeding the passage of tally objects when the channels are at normal raised position and releasing the tally objects therewith when the channels are depressed.

5. In a device of the character described, the combination of a casing, a plurality of elongated channel members relatively parallel in the casing, each channel having the top thereof open providing an elongated slot, springs for resiliently supporting the channel members normally in spaced relation to the inner bottom of the casing, a plurality of tally objects slidable in the channels and extending through the slot thereof for engaging a stop means, a stop means transversely fixed across the slotted openings of the channels intermediate the opposite end thereof for releasably engaging the tally objects, and a press button for depressing the channel members, said press button being upraised from the plane of the slotted opening of the channel members so that the tally objects may pass thereunder, the tally objects being of a size to engage the stop means when the channels are resiliently supported at normal raised position and to pass by the stop means when the channel members are depressed into the casing.

6. A computing apparatus comprising a casing having elongated grooves therein, a plurality of resiliently supported elongated relatively parallel channel members in said grooves and having the tops thereof open providing an elongated slot in each channel, means for resiliently supporting the channel members normally in spaced relation to the bottom of the grooves, a plurality of tally objects slidable in said channels and being of a size to extend through the slots thereof for engaging a stop means, a stop means fixedly mounted transversely on the casing and across the slotted openings of the channels intermediate the opposite ends thereof for releasably engaging the tally objects, a press button for depressing the channel members, said press button being upraised from the plane of the slotted openings of the channel members so that tally objects may pass thereunder, the tally objects being of a size to slide freely under the stop bar when the channel member is depressed into the groove.

7. A device of the character described, including a casing, a plurality of resiliently supported elongated channel members relatively parallel in the casing, each having an elongated slot in its top, spring means for resiliently supporting the channel members in spaced relation to the inner bottom of the casing whereby they may be depressed in the casing, a plurality of tally objects slidable in said channels and extending through the slot thereof for engaging a stop means, a stop means mounted on the casing and transversely across the central portion of the slotted openings of the channels and adapted for releasably en-

7
gaging the tally objects, and means adjacent to the stop bar and upraised from the plane of the slotted opening of the channel members adapted so the tally objects may pass thereunder and under the stop bar.

8. A computing device including a casing, a plurality of relatively parallel elongated channel members in said casing, and of lesser depth than the casing, each of said channel members having an elongated slot at its top, spring means for resiliently supporting the channel members normally in spaced relation to the inner bottom of the casing, a plurality of tally objects slidable in said channels and extending through the slot thereof for engaging a stop means, a stop means mounted fixedly and longitudinally centrally on the casing and transversely across the slotted openings of the channels intermediate the opposite ends thereof, for releasably engaging the tally objects, each of said channel members having adjacent the stop means a manually depressible button for depressing the channel member whereby tally objects may be freed from engagement by the stop bar, said button being upraised from the plane of the slotted opening whereby the 25 tally objects may pass thereunder.

9. In a computing apparatus, the combination of a casing, an elongated channel member in said casing, said channel member having an elongated slot at its top and being adapted for slidably receiving therein a plurality of indicator tally objects, means for resiliently supporting the channel normally in spaced relation to the inner bottom of the groove, a face paralleling said channel and adapted for inscribing numerals thereon, a 10 stop means mounted on the casing independently of the channel member and extending transversely across the slotted top of the channel centrally thereof for obstructing free sliding of tally objects in the channel member, means adjacent the 15 stop means for manually depressing the channel member whereby tally objects may slide clear of the stop bar, said depressing means being upraised from the plane of the slotted opening of the channel members so that the tally objects 20 may freely pass thereunder.
